This technical drawing illustrates a mechanical assembly, likely a ratchet mechanism. At the top, a circular component labeled 9 is shown with a hatched area indicating a slot or track. A lever labeled 18 is positioned vertically, with a circular slot labeled 19 corresponding to the track in component 9. A curved lever labeled 20 is attached to the lower end of lever 18. A curved component labeled 21 is positioned below lever 20. A ratchet wheel labeled 22 is attached to the lower end of lever 18. A curved component labeled 23 is attached to the lower end of lever 22. A vertical slot labeled 13 is visible on the left side. A horizontal slot labeled 24 is located on the right side. A small circular component labeled 7 is located at the bottom left. A small circular component labeled 20 is located at the bottom center.

UNITED STATES PATENT OFFICE.

WILLIAM J. STEWART, OF CHICAGO, ILLINOIS.

FEEDING MECHANISM FOR SEWING-MACHINES.

SPECIFICATION forming part of Letters Patent No. 668,696, dated February 26, 1901.

Application filed March 28, 1900. Serial No. 10,444. (No model.)

To all whom it may concern:

Be it known that I, WILLIAM J. STEWART, a citizen of the United States, residing at No. 2405 Magnolia avenue, Chicago, Cook county, Illinois, have invented certain new and useful Improvements in Sewing-Machine Feed Mechanisms, of which the following is a specification.

This invention relates to improvements in those features of a sewing-machine head which have to do with the feeding forward of the fabric beneath the sewing-needle, and more particularly to an improved mechanism for imparting adjustable movement to the four-motion feed-bar ordinarily employed in this connection. The invention contemplates doing away with the gyratory bar or lever employed for this purpose in many present constructions—such as that shown, for example, in my prior patent, No. 460,730, of October 6, 1891—and the substitution therefor of a rotary or oscillatory shaft provided with a deflected or bent portion adapted to be engaged by connections running to the feed-bar, so that by adjusting said connections along the deflected portion of the shaft the necessary adjustment of the feed movement may be accomplished in the same manner and to the same effect as in the case of gyrating-shaft construction heretofore referred to.

The invention consists in the matters herein set forth, and particularly pointed out in the appended claims, and will be fully understood from the following description of the construction illustrated in the accompanying drawings, in which—

Figure 1 is a bottom plan view of a sewing-machine head provided with my improvements in one form. Fig. 2 is a sectional elevation thereof, taken on line 2 2 of Fig. 1. Fig. 3 is a sectional detail taken on line 3 3 of Fig. 1. Fig. 4 is a fragmentary detail, partly in section, of the stitch-adjusting devices. Fig. 5 is a sectional elevation taken on line 5 5 of Fig. 1 and showing the drive-shaft connections. Figs. 6 and 7 are bottom plan views similar to Fig. 1, showing modified constructions embodying my invention. Fig. 8 is a bottom plan view of a further modification in which the bent shaft oscillates instead of rotating. Figs. 9 and 10 are perspec-

tive details on lines 9 9 and 10 10, respectively, of Fig. 8.

Referring first to the construction shown in Figs. 1 to 5, 1 designates the cast-iron bed-plate of the sewing-machine head, and 2 the usual four-motion feed-bar mounted beneath said bed-plate between depending lugs 3 and 4, the forward end of said feed-bar being provided with a longitudinal slot 5, that embraces a supporting-pin 6, which extends between the lugs 3 and upon which the feed-bar has a pivotal sliding movement. A rotary shaft 7 is journaled longitudinally beneath the base-plate in bearing-lugs 8 and arranged to be rotated, or it may be simply oscillated by any suitable connections with the driving-shaft 9 of the machine. This shaft passes under and supports the feed-bar 2 some little distance back of its supporting-pivot 6, and that portion 10 of the shaft upon which the feed-bar rests is so turned off or provided with an eccentric or is otherwise so formed or bent that as the shaft rotates it imparts a vertical oscillatory movement to the bar. Said shaft is furthermore formed at some point in its length with a bent or deflected portion 11, which constitutes a crank of varying length, and the necessary adjustable longitudinal movement of the feed-bar is accomplished by any suitable operative connections between said bar and the crank so formed. As shown in the construction illustrated in Figs. 1 to 5, the bent portion of the shaft 7 is provided at a point between its bearings 8, and the adjustable connections between said bent portion and the feed-bar consist of a lever 12, one end of which is pivotally secured to the frame by a sliding stud 13, while its other end fits and slides freely through an aperture 14 in said feed-bar. A link 15 connects this lever 12 with the crank portion of the shaft and is herein shown as made in the form of a rigid arm which projects from the lever to the shaft and is provided with a vertical slot 16, through which the latter passes. Then by moving the lever 12 lengthwise by sliding the pivot-stud 13 along within its slot 17 in the bed-plate the link 15 may be slid along upon the shaft 7, so that it will engage the bent or crank portion 11 of the latter either at its point of greatest deflection

or any desirable point of lesser deflection, with the consequent result that the feed-bar will be given a greater or less length of longitudinal oscillatory movement, according to the 5 length of the stitch desired, the maximum amount of deflection of the bend 11 of the shaft and the length of this bend being made such as to afford the full adjustment necessary within the limits of the movement allowed the stud 13 within its slot 17.

As hereinbefore suggested, any suitable means may be provided for imparting rotary or oscillatory movement to the shaft 7 from the driving-shaft 9 of the machine. Such 15 means may conveniently comprise a lever-arm 18, the upper end of which embraces an eccentric 19 of the shaft 9, while its lower end is provided with a wrist-pin 20, which engages a slotted crank-arm 21 on the end of 20 the shaft 7 to rotate the latter, said arm 18 being pivotally supported between its ends by a link 22, which swings about a fixed stud 23 in the machine-arm 24, as better shown in Fig. 5; but it will be understood that such 25 devices constitute in themselves no part of my present improvements.

In the somewhat-modified construction shown in Fig. 6 the bent portion 11 of the shaft 7 is provided at the extremity of the latter beyond the feed-bar and the adjacent bearing 8 of the shaft, and the lever 12 is correspondingly extended beyond said feed-bar to support its connection at a point opposite said deflected portion 11 of the shaft. Adjustment of the length of the stitch will be accomplished in this case, as in the construction first described, by sliding the pivot-stud 13 of the lever 12 longitudinally within its slot 17, so as to move the connecting-arm 15 along the bend to the point of greater or less deflection desired.

In Fig. 7, on the other hand, the bend 11 is provided at the other extremity of the shaft 7 or that end adjacent to the oscillatory arm 18 by which the shaft is rotated. The sliding stud 13 is in this case located between the ends of the lever, and the link or arm 15, which connects the lever with the shaft, is provided at that extremity of said lever opposite to the 45 feed-bar in position to engage the bend of the shaft, as before. Adjustment of the lever-longitudinally by means of its adjusting-stud 13 will then obviously change the length of the stitch in the same manner as in either of the 50 constructions previously described. The bend 11 also constitutes in this case the driving-crank of the shaft, its extremity being to this end shown as projecting into and operatively engaging a slot in the oscillatory arm 18 to 55 receive rotary motion therefrom.

As hereinbefore suggested, the operation of the device will be substantially the same whether the bent shaft rotates or oscillates, and in Fig. 8 I have shown a construction of 65 this latter character in which the oscillatory movement is given to the shaft 7 by a pit-

man 25, leading downwardly from a crank or eccentric 26 on the driving-shaft 9 and connected at its lower end with a crank-arm 27, which may be conveniently formed by bending the end of the shaft into proper shape. Furthermore, the cam for lifting the feed-bar is in this instance made in the form of a separate collar 28, which is adjustably secured upon the shaft 7, beneath the feed-bar, by a 75 set-screw 29. The rocking movement of the shaft accomplished by the pitman connection will then obviously effect substantially the same motion of the feed-bar as in the constructions heretofore described. 80

From the several constructions illustrated it will be understood that my invention is not limited to any particular location of the bend or deflected portion or part or to any particular construction of the shaft 7 or deflected 85 portion or part and the actuating connection between it and the feed-bar, but in its broad aspect includes every form of such adjusting mechanism in which the adjustment is obtained by shifting the point of engagement 90 between the shaft and the connections which lead to the feed-bar along the bent or deflected portion or part of the shaft, so that they will thereby be given a greater or less amplitude of vibration, according to the amount of 95 deflection at the particular point of engagement selected. It will also be understood that a great variety of changes may be made in the details of the construction shown without materially departing from the broad spirit 100 of the invention claimed.

I claim as my invention—

1. In a feed mechanism for sewing-machines, a movably-mounted feed-bar, means for imparting vertical movement to the feed-bar, and means for imparting an adjustable longitudinal movement thereto, comprising a shaft journaled in stationary bearings and provided with a bent or deflected portion, operative connections between said portion and the feed-bar, and means for adjusting said connections along said portion to points of greater or less deflection, substantially as described. 105

2. In a feed mechanism for sewing-machines, a movably-mounted feed-bar, a shaft journaled in stationary bearings and upon which the feed-bar rests, said shaft being so formed beneath the feed-bar as to impart vertical movement thereto, and being provided 110 with a bent or deflected portion, operative connections between said portion and the feed-bar, and means for adjusting said connections along said portion to points of greater or less deflection, substantially as described. 120

3. In a feed mechanism for sewing-machines, a movably-mounted feed-bar, means for imparting vertical movement to the feed-bar, means for imparting an adjustable longitudinal movement thereto, consisting of a 130 shaft journaled in stationary bearings and provided with a bent or deflected portion, a

slidably-pivoted lever operatively engaging the feed-bar, and a connection between said lever and the bent or deflected portion adjustable along the latter to points of greater or 5 less deflection, substantially as described.

In testimony that I claim the foregoing as my invention I affix my signature, in presence

of two subscribing witnesses, this 17th day of March, A. D. 1900.

W. J. STEWART.
